UNITED STATES PATENT OFFICE.

ALLAN D. SKINNER, OF ERIE, PENNSYLVANIA.

STEAM-ENGINE.

1,312,143.

Specification of Letters Patent. Patented Aug. 5, 1919.

Application filed December 20, 1917. Serial No. 208,115.

To all whom it may concern:

Be it known that I, ALLAN D. SKINNER, a citizen of the United States, residing at Erie, in the county of Erie and State of

5 Pennsylvania, have invented certain new and useful Improvements in Steam-Engines; and I do hereby declare the following to be a full, clear, and exact description of the invention, such as will enable others skilled 10 in the art to which it appertains to make and use the same, reference being had to the accompanying drawings, and to the letters of reference marked thereon, forming part of this specification.

15 My invention relates to steam engines of the type wherein the cylinder heads and piston are hollow, and through which engine actuating steam is circulated for the purpose of heating the walls thereof to prevent 20 initial condensation.

The object of my invention is to provide mechanism in a compact form to cause engine steam to flow from one of the hollow cylinder heads or other source of supply 25 thereof into the cavity of the hollow piston then back into said source of supply.

The features of my invention and the operation thereof are hereinafter fully described and pointed out, and are illustrated 30 in the accompanying drawings in which:—

Figure 1 is a vertical central section of a portion of an engine cylinder, cylinder head and piston embodying my invention.

Fig. 2 is a horizontal central section of the 35 same, looking downward.

Fig. 3 is a vertical section through the cylinder head on the line X—X in Figs. 1 and 2.

Fig. 4 is an enlarged detail of a fragment, 40 in vertical central section, showing one of the check valves.

In these drawings A indicates an engine cylinder having central, piston-controlled exhaust ports a and the usual annular exhaust steam duct a' inclosing said ports, and a segmental steam chest or chamber a^2 (see Figs. 2 and 3) thereon, from which port openings a^3 open into the hollow cylinder head B as shown in Figs. 2 and 3. Within 45 the hollow head B are valve seats b — b which are controlled by the valve B', said valve and its operating mechanism B ^{2} being of usual construction.

Within the cylinder A is a hollow piston 50 C which is provided with a piston-rod C' which is secured in said piston in the usual

manner, and is provided with a hollow tail-rod extension C ^{2} , which extends rearwardly through a central opening in the cylinder head B in the usual manner.

60

Within the central opening in the cylinder head B is provided suitable packing C ^{3} , which is held in place by a gland C ^{4} . Within the hollow tail-rod extension C ^{2} is placed a tube D which is secured in concentric, 65 spaced relation to the inner walls of said tail-rod C ^{2} as by means of screw threads d on the inner end thereof. From the inner end of the tube D a duct d' leads into the cavity of the piston C, preferably the forward portion thereof, and from said cavity there is an opening d ^{2} into the space between the tube D and the inner wall of the tail-rod C ^{2} , said opening d ^{2} being preferably provided with a short tube d ^{3} which extends 70 downwardly for the purpose of draining away any water which may accumulate in the piston; the tube d ^{3} being preferably located adjacent to the end wall of the piston C opposite to the exit end of duct d' to insure 75 complete circulation of steam within said piston.

80

Inclosing the tail-rod extension C ^{2} , and secured to the cylinder head B is a cylindrical housing E which is provided with a 85 chamber E' into which the tail-rod C ^{2} projects, and with a cylindrical projection or sleeve E ^{2} , which is adapted to enter the central opening in the hollow cylinder head B and engage the gland C ^{4} and press it 90 against the packing C ^{3} . Within the tube D there is a tube F, which is provided with packing rings f or other suitable means adapted to form a substantially steam tight fit with the inner wall of the tube D, the 95 rear or outer end of said tube F being secured in the rear or outer end of the housing E as by means of threads f', said tube F communicating with a chamber e in the rear or outer end of the housing E.

100

I provide a duct or passage e' leading from the cavity in the cylinder head B to the chamber e in the rear end of the housing E, said passage being provided with a valve seat e ^{2} where it enters said chamber 105 e; and through the wall opposite said valve seat e ^{2} I provide an opening e ^{3} sufficiently large to permit the forming of said valve seat and the insertion of a check valve G, which is provided with a stem G' which extends into a screw-threaded thimble plug H adapted to close the openings e ^{3} . Within 110

the thimble plug H, the valve stem G' is provided with an enlarged guide portion g (see Fig. 4) which has a longitudinal groove g' to permit the passage of air or steam therethrough to insure the free movement of the guide portion g in the thimble H; and within said thimble H, and under the valve-stem guide g I place a spring J of sufficient strength to counterbalance the valve G and normally maintain the same seated. I also provide a duct or passage K which leads from the chamber E' in the housing E, into the cavity in the cylinder head B which is provided with a check valve L of similar construction to the valve and thimble G and H. While other forms of check valves may be used, I prefer the form herein shown and described, because of its convenience in construction and adjustment; the latter feature being accomplished by the screw-threaded thimble plug H.

Secured to and communicating with the segmental steam chests a² at each end of the cylinder A is a branch pipe M to which the throttle-valve N is connected, by means of which the supply of engine actuating steam is admitted to the engine.

In operation engine actuating steam is admitted to the steam chests a² and passes through the ports a³ into the cavity in the head B, and into the ducts or passages e' and K, and upon the raising of the valve B' through the ports b' into the cylinder A which causes the piston C to move forwardly therein. Upon the forward movement of the piston C the tail-rod C² and tube D therein move forwardly while the tube F remains stationary, thus lowering the pressure within the piston C, duct d', tubes D and F, and chamber e, which permits engine actuating steam in the duct or passage e' to press the check valve G open and flow into the chamber e and tubes F and D, and thence through the duct d' into the piston cavity. Then during the return movement of the piston C, the shortening of the telescoping tubes D and F compresses the steam within the piston cavity, tube d³ and space within the tail-rod C² around the tube D therein, and chamber E' in the housing E until it presses the check-valve L open and flows through the duct or passage K back into mass of engine actuating steam in the cavity of the cylinder head B.

It will thus be seen that by means of the mechanism herein shown and described, I am enabled to alternately draw engine actuating steam from the supply thereof, into the cavity in said piston, and then compress said steam sufficiently to force it back into the supply of engine actuating steam, whereby the walls of said piston are heated sufficiently to prevent initial condensation on the ends of the piston, and also to transmit sufficient heat to the wall of said cylinder ad-

jacent to the exhaust ports to dry any moisture which may form thereon, there to lessen condensation of engine actuating steam within said cylinder. The amount or quantity of steam thus circulated through the piston cavity is governed by the speed of the engine.

It will also be seen that by reversing the valves C and L the flow of steam through the ducts e' and K will be reversed without effecting any substantial change in the results of the operation of my invention.

Having thus shown and described suitable mechanism for embodying my invention, I do not desire to limit myself to the exact form shown and described, as it is evident that my invention may be utilized in several different ways without departing from the scope of my invention; therefore what I claim and desire to secure by Letters Patent is:—

1. In a steam engine, a cylinder, an inlet valve chamber in communication with said cylinder, a piston in said cylinder having a cavity therein, a hollow tail-rod secured to said piston and communicating with the cavity therein, a housing inclosing said tail-rod, a pair of telescoping tubes arranged in spaced relation within said tail-rod one tube being secured to and moving with said tail-rod, and the other being stationary and secured to the outer end of said housing, a duct leading from said inlet valve chamber to the outer end of said stationary tube, a non-return valve therein, a duct leading from the interior of said housing to said inlet valve chamber and a non-return valve therein.

2. In a steam engine, a cylinder, an inlet valve chamber in communication therewith, a hollow piston within said cylinder, a hollow tail-rod secured to said piston and communicating with the interior of said hollow piston, a stationary housing inclosing said tail-rod, a pair of telescoping tubes within said hollow tail-rod, one tube being secured within and reciprocating with said tail-rod and communicating with the interior of said piston and the other of said telescoping tubes being stationary and secured to the outer end of said housing, a duct leading from said inlet valve chamber to the outer end of said telescoping tubes, a non-return valve to control said duct, means to adjust said valve, a duct leading from the interior of said housing to said inlet valve chamber, a non-return valve to control said duct, and means to adjust the same.

3. In a steam engine, a cylinder, a valve to admit steam into the end thereof, means to operate said valve, a head on said cylinder having a central opening therethrough, a piston in said cylinder having an interior cavity, a hollow tail-rod secured to said

5 piston and extending through the central opening in said cylinder head and communicating with the piston cavity, a housing secured on said cylinder head inclosing and in spaced relation to said tail-rod, a tube secured within said tail-rod in concentric spaced relation to the inner wall thereof and in communication with the interior cavity of said piston adapted to reciprocate 10 with said tail-rod, a stationary tube secured in the outer end of said housing and telescoping with the last mentioned tube, a valve chamber in the outer end of said housing communicating with said last mentioned 15 tube, a check valve therein, means to conduct engine actuating steam to said check valve, a valve chamber communicating with the interior chamber in said housing, a check valve therein, and means to admit engine 20 actuating steam to the rear side of said last mentioned check valve.

4. In a steam engine, a cylinder, a hollow head therefor, means to convey engine actuating steam into said hollow head, a piston 25 in said cylinder having a cavity therein, a hollow tail-rod secured thereon and communicating with said cavity, a housing secured on said hollow head and inclosing said tail-rod, a pair of telescoping tubes within said 30 tail-rod one tube being secured in and reciprocating with said tail-rod and communicating with the cavity in said piston, and the other or stationary tube being secured in the inner end of said housing, a valve 35 chamber within the outer end of said housing communicating with the outer end of said stationary tube, a duct leading from the interior of said hollow cylinder head to said valve chamber, a non-return valve in said

valve chamber to control said duct, a duct 40 leading from the interior of said housing to the interior of said hollow cylinder head, a non-return valve to control said duct, whereby a volume of engine actuating steam equal to the cubic volume of 45 the stroke length of the tail-rod is circulated through the hollow piston at each reciprocation thereof.

5. In a steam engine, a cylinder, a head therefor, a hollow piston, a hollow tail-rod 50 secured to said piston communicating with the interior of said piston, and extending rearwardly through said head, telescopic tubes within said tail-rod and communicating with the interior of said piston, a 55 housing inclosing said tail-rod, a source of engine actuating steam supply for said engine, a duct leading from said source to said telescopic tubes, a non-return valve in said duct, a duct leading from said housing to 60 said source of motive steam supply, and a non-return valve therein, whereby a portion of the supply of engine actuating steam will be circulated through said hollow piston.

6. The combination with a steam engine 65 cylinder having a steam supply passage thereto, and a hollow piston in the cylinder, of a steam chamber on the cylinder head, a valved connection between said passage and chamber, a hollow tail rod projecting 70 from the piston and connecting the interior of said piston and the chamber, to admit steam to the former, and means to return steam from the piston to said passage, including a check valve opening toward said 75 passage.

In testimony whereof I affix my signature.
ALLAN D. SKINNER.
